UNITED STATES PATENT OFFICE.

GEORGE A. ROBINSON, OF BOSTON, MASSACHUSETTS, ASSIGNOR TO PNEUMATIC SCALE CORPORATION, LIMITED, OF QUINCY, MASSACHUSETTS, A CORPORATION OF MAINE.

CARTON-BLANK.

1,140,288.

Specification of Letters Patent. Patented May 18, 1915.

Original application filed July 7, 1914, Serial No. 849,396. Divided and this application filed December 14, 1914. Serial No. 877,033.

To all whom it may concern:

Be it known that I, GEORGE A. ROBINSON, a citizen of the United States, residing at Boston, county of Suffolk, State of Massachusetts, have invented a certain new and useful Improvement in Carton-Blanks, of which the following is a specification, reference being had therein to the accompanying drawings.

10 This is a division of an application by me for machine for forming cartons, filed July 7, 1914, Serial No. 849,396.

The invention relates to a new and useful improvement in blanks for the formation of 15 cartons.

The invention has special reference to a blank for the formation of that class of cartons made of a single sheet of paper in which the carton has four side forming 20 panels and a side sealing lap and four end forming flaps for each end of the carton. In the formation of the carton the blank is intended to be folded first into tubular form and the side sealing lap sealed and then the 25 bottom forming flaps are folded leaving the top closing flaps open as they are not to be folded until after the carton is filled. Cartons made in this way are intended to be immediately conveyed to the filling mechanism as soon as the carton is formed and set 30 up as distinguished from so-called knock down cartons which are first made in the knock down form for convenience of packing and transportation or to be stored away 35 for future use.

The present invention is intended to enable blanks to be made in quantities all of uniform size and character for use in making up on a carton forming machine but the 40 blanks are formed independently of and separate from the carton forming machine so that they may be ready for use whenever desired for forming into cartons instead of, as is sometimes done, cutting the blanks 45 from a web of paper and feeding them directly into the carton forming machine. The blanks are particularly intended for use in a carton forming machine in which the blanks are piled up in a stack in a magazine and the lowermost blank is withdrawn 50 from the magazine and delivered to the carton forming mechanism. In forming the carton out of these blanks it is intended to have the blank made into tubular form

around a rectangular forming block so located that the carrier mechanism may carry the blank from the stack to the forming block, and it is still more especially intended for use in a machine of the character shown and described in an application filed 60 by me July 7, 1914, Ser. No. 849,396, of which this is a division. In this type of machine it is intended to apply adhesive to all except that one of the bottom closing flaps which is to be the one last folded before the 65 blank leaves the stack and also to apply adhesive to the side sealing lap while it is being withdrawn from the stack or magazine. Said machine also contains means for gripping a portion of the blank which forms a 70 part of the end forming flaps and reciprocating said gripping mechanism so that it may seize the blank and withdraw it from the bottom of the stack. In order to enable the gluing mechanism to have access to the 75 sealing flap portion of the blank while it is still in its position at the bottom of the stack and also so that the gripping mechanism may have an opportunity of gripping it the magazine is so formed that the flap 80 forming portions for forming the bottom are unsupported on the under side. It is intended to have the gripping mechanism seize the blank after the adhesive has been applied to the sealing flaps but to grip it at 85 some other portion of the bottom forming flaps than that to which the adhesive is applied so that the gripping mechanism will not become smeared with the adhesive. Inasmuch as there is no bottom support for 90 the flaps it is found that it is a great advantage and will retain the blank in better form for the feeding mechanism if the end forming flap which is to be gripped remains tied laterally to the adjacent flaps until after 95 the flap is seized by the gripping mechanism.

In the machine shown in the application above referred to in order to enable the gripping mechanism to seize the lowermost blank a separator device is inserted between the 100 unglued flap of the lowermost blank and the one immediately above it so as to afford an entrance for one of the gripping jaws, the other gripping jaw engaging the said flap on the under side. After the blank is once 105 seized by the grippers there is no further need of the union between the unglued flap and the two adjacent flaps and therefore as

it is necessary to have the union separated before the end flaps are folded some means are provided for completing the slit to the end of the flaps, thus making complete the 5 four end forming flaps. The particular means for completing this severing operation is shown in the application above referred to but as the severing mechanism in itself forms no part of the present division 10 of said application the severing device is not shown or described herein.

The invention will be fully understood from the following description taken in connection with the accompanying drawings 15 and the novel features thereof will be pointed out and clearly defined in the claims at the close of the specification.

In the drawings,—Figure 1 is a plan of a blank embodying the invention. Fig. 2 is an 20 elevation partly in section showing the magazine with a stack of blanks and a portion of the mechanism for applying adhesive to the end forming flaps and showing the separator device engaged beneath the lowermost blank, 25 the gluing mechanism being at the outer end of its stroke. Fig. 3 is a side elevation partly in section showing a portion of the same apparatus as in Fig. 2 with the gluing 30 device engaged with the blank and the separator finger just about entering between the lowermost blank and the one above it after the separating fingers have been fully moved back from the position of Fig. 2 and again moved forward. Fig. 4 is an elevation of a 35 portion of the flap gluing mechanism.

The blank 1 is cut and scored to form four panel portions *a*, *b*, *c*, *d*, which are to form the four side panels of the body of the carton, a side sealing lap *e*, four end flaps *f*, *g*, *h*, *i* 40 to form the bottom of the carton and preferably four end flaps *j*, *k*, *l*, *m* to close the top of the carton after it is filled. The blank is scored along the lines indicated by the dotted lines to facilitate folding and the 45 full lines between the end closing flaps indicate where it is cut through. It is to be noted that the lines of cut *n*, *o* between flaps *f* and *g* and between *g* and *h* respectively do not extend quite to the outer edge of the 50 flaps so that there is still a slight union between the said flaps *f*, *g* and between the flaps *g*, *h* which can be easily severed at the proper time, while the line of cut *p* between the flaps *h* and *i* and the lines of cut between 55 all of the top closing flaps are cut clear to the outer edge. The reason for this is that it is desired to retain the flaps *f*, *g* and *h* in better supporting connection with each other, as already referred to, and to prevent any one 60 of said three end flaps from dropping one below the other when they project from the holder or magazine preliminary to the gluing, and so that the flap *g* will be bent down with the flaps *f* and *h* by the action of the 65 gluing pad and so that when the separator

ingers enter between the lowermost blank and the stack above the lowermost blank, the separator fingers will slightly lift the flaps *f*, *g*, *h* of the stack as shown in Fig. 2, thus allowing space for the grippers as will 70 appear more clearly in the description hereinafter. In applying adhesive it is intended to apply it to the outer faces only of the flaps which are to be glued, that is, on the faces, which, when the blank is folded, will 75 face outward from the forming block rather than toward the forming block. In the particular form of blank shown it is intended that the two flaps *f*, *h* shall be folded before the flaps *g*, *i*. These two flaps *f*, *h*, which 80 are shorter than the other two flaps may either overlap each other or simply come to a meeting edge and when the flap *i* is folded over onto the glued faces of the flaps *f*, *h* and then the flap *g* will be folded over onto 85 the outer face of the flap *i* which has the adhesive. It is therefore unnecessary to apply adhesive to the flap *g*, and that is the one which is intended to be seized by the grippers to draw the blank out from the 90 stack and deliver it to the carrier which will transfer it to the proper position to be formed into shape on the forming block.

It has not been deemed necessary to show in the present division of the application 95 all of the mechanism for gluing the flaps and for handling the blank in withdrawing it from the magazine and carrying it to the carton forming mechanism but a portion of the apparatus is shown for the purpose of a 100 little more clearly illustrating the advantage of the invention. The holder or magazine in which the blanks 1 are stacked up consists of a plurality of horizontal rolls 2 spaced apart from each other in the form of a grid 105 on which the pile of blanks rests and four upright corner posts 3 consisting of angle bars 3 which have wings at right angles to each other so that each post will have faces which engage two edges of the blank. In 110 the drawings only two of these upright posts or angle bars 3 are shown, namely, those which are at one side of the stack of blanks. The other two corner posts are similar, the said corner posts being disposed in such 115 manner as to be at the four corners of a rectangle.

The rolls 2 are journaled in the frame of the machine. Rolls are employed for the 12 bottom supports so that the bottom blank may be more easily drawn out from beneath the weight of the other blanks in the stack. It will be noted from the drawings that these bottom supporting rolls are beneath the body of the blank which forms the side 125 forming panels and also are beneath the end closing flaps for one end of the carton, namely, those which are to close the top, but there are no rolls beneath the end closing flaps at the other end of the blank, namely, 130

those which are to close the bottom. This is to enable the gluing pad to have access to the bottom closing flaps and also to enable the flaps of the lowermost of said blanks to be bent down preliminary to the engagement by the grippers.

Mounted on the shaft 8 is a spur gear 13 which engages with a stationary rack 14 so that as the carriage 9 reciprocates the shaft 8 will rotate in one direction or the other according to the direction of travel of the carriage. Mounted fast on shaft 8 is a lever 15 having a segmental face on which are mounted the segmental gluing pads 18, 19 which serve to apply adhesive to the flaps *f*, *h* and *i* of the blank. The pad 18 is of a suitable width and location on the holder to apply adhesive to the flap *f* and the pad 19 is of a greater width so as to apply adhesive to the adjacent flaps *h* and *i*. The outer periphery of these pads is concentric with the shaft 8. As the carriage 9 reciprocates the engagement of the gear 13 with the rack 14 will cause the pads to swing around in the arc of a circle.

Mounted on a shaft 20 journaled in the frame of the machine is a glue feed roll 21 which is kept supplied with glue in any suitable manner. A gluing roll 23 is journaled in the swinging ends of the two parallel levers 24 which are respectively pivoted at their other ends to the carriage 9. A spring 25 under tension fastened at one end to the carriage and fastened at its other end to one of the levers 24 and a similar spring connected with another part of the carriage and with the other lever 24 tend to pull the levers 24 and the roll 23 upward. When the carriage 9 is in its rearward position the gluing roll 23 will bear against the glue feed roll 21 as shown in Fig. 2 and the gluing pad will extend rearwardly. When the carriage moves forward, that is, to the right as viewed in Fig. 2, the glue pad holders and pads will by reason of the rotary movement of the spur gear 13 swing forward and then up and over into the position shown in Fig. 3 and in so doing the outer faces of the pads will wipe along over the periphery of the glue feed roll 23, the said glue feed roll yielding backward to permit the pads to sweep past and then the springs 25 will bring the levers 24 and pads back into the position shown in Fig. 3, and in so doing the pads will wipe the under surface of the flaps *f*, *h*, *i*, and on the return movement of the carriage the pad holders and pads will rotate backward.

As the glue pads 18, 19 roll over the flaps *f*, *h* and *i* the glue will cause those flaps to slightly adhere to the pads and be bent down as shown in Fig. 3. As flaps *f* and *h* are thus pulled down, they will bend the flap *g* down with them. This allows the insertion of a separating finger between the glued

flaps *f*, *h* and the overlying flaps of the carton above it so as to slightly separate the flaps of the two blanks and admit the upper jaw of the gripping device which is to pull the blank from the stack. The separator device shown in the drawings consists of one or more levers 46 mounted on a rocker shaft 47 and each formed with a foot 48, said levers being so located that they will be rocked by the shaft 47 in such a way as to cause the foot of the lever to enter between the slightly downwardly bent glued flaps *f*, *h* and the flaps of the overlying blank. Although only one of said levers 46 is shown in the sectional view of the drawings another similar lever is mounted on the same rocker shaft 47 at a sufficient distance apart so that the blank will be engaged at two different points.

In Fig. 3 the separator fingers are just about to enter between the lowermost blank and the stack above it. It will swing farther forward into the position shown in Fig. 2 and slightly lift the flaps of the blanks above it. The separator will remain in this position while the lowermost blank is being withdrawn. When the bottom forming flaps of the lowermost blank are thus separated from the blank above it the gripping mechanism for withdrawing the blank has opportunity to seize the blank.

In the original application of which this is a division said gripping and withdrawing mechanism is fully shown and described and shows means for severing the union between the flaps *f*, *g*, and the flaps *g*, *h* at their outer ends in continuation of the slits *n*, *o*. It is not deemed necessary in the present divisional application to show or describe in detail that mechanism.

What I claim is:

1. An unfolded blank for a carton consisting of a flat unfolded sheet having scored lines along which the sheet is to be folded to form the body of the carton, flaps at one end of the blank for forming the bottom of the carton, said bottom forming flaps being extensions respectively of the panels for the body of the carton, an intermediate one of said bottom forming flaps being partially separated from the adjacent flap by a slit at the side of said intermediate flap and in alignment with the said folding line between the panels and which extends from the end of said folding line between the panels and the flaps toward the outer end of the flap but stopping short of the end, thereby leaving a slight union for the flaps at their outer ends.

2. An unfolded blank for a carton consisting of a flat unfolded sheet having four panel portions with scored lines between them along which the blank is to be folded to form the body of the carton, a sealing lap portion on one side of one of the outer panel

portions of the blank, flaps at one end of the blank for forming the bottom of the carton, said bottom forming flaps being extensions respectively of the panels for the body of the carton, an intermediate one of said bottom forming flaps being partially separated from the two adjacent flaps by slits at both sides of said intermediate flap in alignment with the said folding lines and which extend 10 from the ends of the said folding lines between the panels and between the flaps toward the outer end of the flap but stopping short of the end thereby leaving a slight union for the flaps at their outer ends.

15 3. An unfolded blank for a carton consisting of a flat unfolded sheet having four panel portions with scored lines between them along which the blank is to be folded to form the body of the carton, a sealing 20 lap portion on one side of one of the outer panel portions of the blank, flaps at one end of the blank for forming the bottom of the carton, said bottom forming flaps being ex-

tensions respectively of the panels for the body of the carton, an intermediate one of 25 said bottom forming flaps being partially separated from the two adjacent flaps by slits at both sides of said intermediate flap in alignment with the said folding lines and which extend 30 from the ends of the said folding lines between the panels and between the flaps toward the outer end of the flap but stopping short of the end thereby leaving a slight union for the flaps at their outer ends, the bottom forming flap which is an 35 extension of one of the outside panel portions being separated from the flap of the adjacent panel by a slit in continuation of the folding line between said panels which continues clear to the outer end of the flap.

In testimony whereof I affix my signature, in presence of two witnesses.

GEORGE A. ROBINSON.
